DESIGN FOR A HEAD FOR A HAND MIRROR OR SIMILAR ARTICLE

Edward Marder, Brooklyn, N. Y.

Application May 22, 1939, Serial No. 85,120

Term of patent 3½ years

To all whom it may concern:

Be it known that I, Edward Marder, a citizen of the United States and a resident of Brooklyn, in the county of Kings and State of New York, have invented a new, original, and ornamental Design for a Head for a Hand Mirror or Similar Article, as shown, of which the following is a specification, reference being had to the accompanying drawing, forming a part thereof.

The dominant features of my design reside in the portion shown in full lines.

I claim:

The ornamental design for a head for a hand mirror or similar article, substantially as shown and described.

EDWARD MARDER.
